CLAIM

The ornamental design for a grommet assembly having electrical power receptacles for use with a work surface, as shown and described.

DESCRIPTION

FIG. 1 is a top perspective view of the grommet assembly having electrical power receptacles for use with a work surface showing our new design;

FIG. 2 is another perspective view thereof;

FIG. 3 is a right side elevational view thereof;

FIG. 4 is a left side elevation view thereof;

FIG. 5 is a rear elevational view thereof;

FIG. 6 is a front elevational view thereof;

FIG. 7 is a top plan view thereof; and,

FIG. 8 is a bottom plan view thereof.

In the drawings, the broken lines are for the purpose of illustrating portions of the grommet assembly having electrical power receptacles for use with a work surface that form no part of the claimed design.

1 Claim, 8 Drawing Sheets
